CLAIM

The ornamental design for a reusable filter frame for filter media as shown and described.

DESCRIPTION

FIG. 1 is a perspective view of a new design for a reusable filter frame for filter media;
FIG. 2 is a left view thereof;
FIG. 3 is a right view thereof;
FIG. 4 is a front view thereof;
FIG. 5 is a rear view thereof;
FIG. 6 is a top view thereof; and,
FIG. 7 is a bottom view thereof.

The portions of the reusable filter frame for filter media depicted in broken lines in FIGS. 1-6 form no part of the claimed design.

1 Claim, 5 Drawing Sheets
